ELECTRIC FLATIRON

Bernhart A. Benson, Chicago, Ill., assignor to Chicago Electric Manufacturing Company, Chicago, Ill., a corporation of Illinois

Application October 6, 1938, Serial No. 233,643

12 Claims. (Cl. 38—79)

This invention relates to an electric flatiron and more particularly to the interlocking construction of the several parts.

It is an object of this invention to provide a shell, a terminal or plug receiving housing and a back rest of such construction that these several parts may be inexpensively manufactured, preferably from sheet metal, and readily assembled in rigid interlocking relation with each other and with the other parts of the flatiron including the handle support to provide a streamlined flatiron.

A further object of the invention is to provide a flatiron embodying a shell and back rest of individual pieces whereby the shell effectively retains the heat within the iron as against loss due to convection, while at the same time the back rest is maintained at a temperature permitting its satisfactory use for the intended purpose.

Applicant's invention further contemplates the provision of a streamlined iron of the character stated wherein the pieces constituting the shell and rest are of such construction as to facilitate their interlocking assembly with a minimum of manufacturing steps and are of such construction as to prevent articles being ironed from catching or tearing on the edges of the several pieces when in assembled relation.

Another object is to provide a handle support having means for supporting the terminal housing and/or for fastening the back rest to the shell.

Other and further objects and advantages will be apparent from the following description when taken in connection with the accompanying drawings, wherein:

Fig. 1 is a view in perspective of an electric flatiron embodying the invention.

Fig. 2 is a plan view, partly in section, taken along the line 2—2 of Fig. 1.

Fig. 3 is a vertical section along the line 3—3 of Fig. 1.

Fig. 4 is an exploded view in perspective of the shell, the terminal or plug receiving housing, the back rest and a reinforcing member for the back rest.

Fig. 5 is a view in perspective of a flatiron embodying a modification of the invention shown in Figs. 1 to 4.

Fig. 6 is a plan view, partly in section, along the line 6—6 of Fig. 5.

Fig. 7 is a vertical sectional view taken along the line 7—7 of Fig. 5.

Fig. 8 is an exploded view in perspective, fragmentarily showing the shell and back rest.

As shown in Figs. 1 to 4, a flatiron embodying the invention comprises the usual sole plate or heat applying member 9, a heating element or means 10 and a pressure or clamping plate 12 overlying the heating element 10 and attached to the sole plate in any conventional or desired manner as by screws 13 passing through openings in the heating element. The shell 14 preferably comprises a sheet metal stamping formed along its median longitudinal plane with spaced, substantially rectangular grooves or recesses 16 and a central, generally circular groove or recess 17. The shell is provided with outwardly curved reinforcing and streamlining ribs or ridges 18 extending from end to end and spaced symmetrically with respect to the median longitudinal plane of the shell.

A handle 20 is provided at its opposite ends with grooves 22 receiving the upper free ends of supporting straps 24 and 26, the handle being secured to the straps by means of a bolt 28. The sole plate 9 may be provided with the usual upstanding flange or with spaced lugs (not shown) for properly positioning the shell with respect thereto.

A back rest 30 preferably comprises a hollow sheet metal streamlined stamping having a convex top surface or wall 32, so shaped as to merge into the forward or toe portion of the shell and be symmetrical with said portion of the shell about the point of maximum height of the shell. The back rest is also formed with convex side flanges 34 and a rear flange 36 forming a depending skirt. The upper surface or top wall 32 extends forwardly beyond the side flanges to provide a tongue 38 formed with depressed portions 40 providing grooves to receive the inturned ends 42 of the handle straps 24 and 26 and projections or bosses for seating within the grooves 16 in the shell 14 for interlocking the shell and back rest. The rear edge of the back rest 30 is made concave to provide spaced points of support 44 lying substantially in the planes of the bottom edges of the depending side flanges 34 and the side flanges 34 at their forward edges 45 are curved as at 46 to conform to the shape of the rear portion or heel of the shell so that they may be brought into contacting relation therewith and with the ribs or ridges 18 so that these side flanges, as well as the rear flange and the upper wall, support the iron in vertical position. The back rest is additionally formed with a circular depressed portion 47, midway between the depressed portions 40, to form a groove for receiving a circular plate and a boss for seating 55

within the circular groove 17 of the shell to still more rigidly interlock the shell and rest member at their assembled point of symmetry. A streamlining and reenforcing ridge or rib 48 encircles the forward half of the groove 17 and extends to the points 44 along the imaginary line at which the side flanges would merge into the top wall or surface.

An opening 49 adjacent the rear edge of the shell 14 permits the terminal prongs 50 to be projected therethrough. These terminal prongs are preferably carried by a resilient strap 52 secured to an upstanding bracket portion 54 of the clamping plate 12, the terminal lugs 50 being secured to, but insulated from, the strap and being electrically connected to the heating element 10 in the customary fashion. The strap 52 is provided at its rear edge with a rearwardly extending lug 56 received within a notch 58 at one side of the opening 49 to properly position the terminal lugs within the opening 49. The back rest 30 is provided with an opening 60 similar to the opening 49 and aligned therewith when the back rest has been fastened to the shell.

The terminal or plug receiving housing 62 is preferably formed of a single piece of sheet metal bent to the general form of an ellipse in cross section and provided at its rear lower edge with a rearwardly extending skirt 64 overlying the back rest 30 and with a depending and rearwardly extending lug 66, the lug 66 being received within a slot 68 in the upper wall 32 of the back rest 30. The lug 66 is of reduced size so as to form shoulders 70 for supporting the terminal housing on the back rest. At its forward edge the housing 62 is formed with a depending lug or lugs 72 which are received within the groove formed by the rear depressed portion 40 of the tongue 38 of the back rest so as to offer a further support for the terminal housing.

The terminal housing 62 is additionally supported by the rear handle supporting strap 26 by means of a depending lug 74 struck out from the strap 26 and projecting through a slot 76 in the terminal housing into contact with the inner surface of the housing. The handle strap 26 and the back rest 30 are fastened to the shell 14 by means of screws or bolts 78 passing through the inturned ends 42 of the straps 24 and 26, the depressed portions 40 in the tongue 38 of the back rest, and through the shell into the bracket portion 54 of the clamping plate.

The terminal housing 62 is interlocked with the back rest 30, by the lugs 66 and 72 and with the handle strap 26, by the lug 74 and this housing is provided at its upper rear edge with a backwardly extending tongue 82 forming a third point of support for the iron when in vertical position. Since the terminal housing is interlocked in contacting relation with the handle strap 26, it provides, through the handle, a very rigid additional support for the iron when the iron is in vertical position.

The circular depressed portion 47 of the back rest and the circular groove 17 are apertured to receive the switch control and temperature adjusting stud 83 threaded for vertical adjustment in the bracket portion 54, the stud 83 bearing against the adjustable control switch member 84 of a temperature controlled switch unit which may be of conventional structure. The circular depressed portion 47 receives an index disk or plate 86 surrounding the stud 83 and secured to the back rest as by lugs 87 for cooperation with

a control knob 88 screwed onto the end of the stud 83.

In the case of flatirons of the larger sizes, additional reinforcement of the back rest may be desirable. In this event the reinforcing member 90 may advantageously be employed. This reinforcing member preferably comprises a piece of sheet metal bent as shown in Figs. 3 and 4 for reception within the hollow back rest 30. This member preferably is substantially V-shaped in longitudinal section and provides a supporting base or leg 92 and a reinforcing arm 94. The base 92 is supported on the sole plate 9 of the flatiron and is provided at its free edge with spaced, forwardly projecting lugs 96 received within spaced notches 98 in the rear wall 100 of the shell 14. The reinforcing arm 94 of the member 90 engages the under surface of the top wall 32 of the back rest 30 and is interposed between this wall 32 and the attaching lug 66 of the terminal housing 62, the arm 94 being provided at its free edge with a notch 102 for receiving the depending portion of the lug 66.

The shell, the back rest, the terminal housing and the handle may be readily assembled and interlocked as follows. The shell 14, the back rest 30, and the reinforcing member 90 if employed, are first assembled by inserting the lugs 66 of the reinforcing member 90 through the notches 98 of the shell, then by placing the back rest 30 on the reinforcing member with the projections formed by the depressed portions 40 of its tongue 38 seated within the grooves 16 of the shell, and with the forward portion of the back rest confined within the ribs or ridges 18 so that when in use the articles being ironed will not catch upon the edges of the back rest. The terminal housing 62 is then placed in position by inserting the lug 66, preformed as shown in the drawings, through the opening 68 in the back rest, and through the notch 102 in the reinforcing member. The terminal housing is then swung forwardly until the lug or lugs 72 are properly seated within the groove provided by the rear depressed portion 40. The slot 68 in the back rest is sufficiently enlarged to permit this swinging of the terminal housing. The handle, the parts of which have been previously assembled, is then brought down upon the shell so as to cause the inturned ends 42 of the straps 24 and 26 to seat within the grooves 16 of the shell and within the grooves formed by the depressed portions 40 of the back rest. In being brought down upon the shell, the lug 74 of the rear handle strap is caused to press through the slot 76 of the terminal housing and into contact with the inner wall of such housing. The assembled shell, rest, terminal housing and handle are then assembled within the sole and clamping plates and the screws 78 placed in position, thereby securing the handle, the back rest, and the terminal housing in interlocked relation and to the clamping plate, the terminal housing and shell in turn securing the reinforcing member in interlocked relation with the back rest. The knob 88 is finally secured to the projecting control 83.

In the form of the invention shown in Figs. 5 to 8, the handle supporting strap 104 is of the one piece type secured at its central point to the pressure and clamping plate 106 which is superimposed upon the insulated heating plate 108. The base of the strap 104 is received within a groove 110 extending longitudinally in the median plane of the shell 112. The handle strap and the shell are secured to the clamping plate 75

106 by means of a screw threaded rod 114 bolt-
ing the clamping plate to the sole plate and re-
ceiving a threaded sleeve 116 passing through the
5 handle and the shell, the sleeve 116 having an
enlarged head 118 overlying a facing strip 120 in-
terlocked with the handle strap by end lugs 122
received in notches formed at the intersection of
the arms with the base of the strap.

The shell 112 at the rear of the longitudinal
10 groove 110 is further depressed to form a groove
124 in communication with, but having its base
below, the plane of the base of the groove 110.
The groove 124 receives the boss 126 formed at,
15 and extending inwardly from, the forward free
edge of the flat, downwardly inclined upper wall
128 of the back rest 130. The back rest 130, sim-
ilarly to the back rest 30, is provided with con-
vex side portions or flanges 132 and a concave
20 rear flange 134. The terminal housing 136 is
identical to the terminal housing 62 of Figs. 1 to
4 and is similarly interlocked with the back rest
130 and the handle strap 104.

The back rest 130 is fastened to the shell 112
by a downwardly and rearwardly extending lug
25 138 struck out from the handle supporting strap
104 and passing through aligned slots in the boss
126 and the bottom of the groove 124. The shell
112 is formed with outwardly curved reenforcing
30 and streamlining ribs or ridges 140, 142, 144 and
146, the ribs 140—142 intersecting adjacent the
toe edge of the shell and extending to the oppo-
site corners of the heel edge of the shell, and the
35 ribs 144—146 extending from the rear edge of
the groove 110 to intersect the ribs 140—142 at
the heel corners of the shell. The tongue por-
tion of the back rest 130 is confined between the
ribs 144—146 so that when in use the articles
being ironed will not catch upon the edges of the
back rest.

40 In this form of the invention the shell 112, the
back rest 130 and the reenforcing member 90, if
employed, are first assembled by associating the
reenforcing member with the shell and then by
45 placing the back rest over the reenforcing mem-
ber with the boss 126 seated within the groove 124
of the shell 112. The terminal housing 136 is
then placed in position as previously described
50 with reference to the terminal housing 62. The
handle strap 104, with which the handle has al-
ready been assembled, is then brought down into
position with the lug 138 extending through the
55 boss 126 and the base of the groove 124 and with
the attaching lug 74 for the terminal housing
136 in proper interlocked relation with such hous-
ing. The bottom edge of the lug 138 is then bent
over into contacting engagement with the inner
60 surface of the shell, thus interlocking the handle,
the housing, and the reenforcing member to the
shell. These interlocked parts are then fastened
to the clamping plate of the iron by means of
the single threaded sleeve 116.

It will be seen from the foregoing description
65 that applicant has provided an inexpensive and
simply constructed streamlined electric flatiron,
the parts of which may be easily assembled in
rigid interlocking relation, and in which the shell
and back rest are made of individual pieces so
70 that the shell may completely enclose the heating
unit to prevent loss of heat from the shell due to
convection and the back rest is maintained at
proper temperature for satisfactory use for its in-
tended purpose. It is also to be noted that al-
75 though constructed in separate pieces the shell
and back rest are so formed that upon assembly

no free edges are left exposed to catch and tear
articles being ironed.

The invention is hereby claimed as follows:

1. In a flatiron, a heat applying member,
means for heating said member, a shell for en-
closing said heating means, means securing the
shell to the heat applying member, and a rest
member for supporting the iron, said shell and
said rest member comprising individual pieces of
sheet material formed for ready assembly in rigid 10
interengaging and contacting relation with each
other, the rest member having forward edges
merging into the shell at points of contact, said
shell having an outwardly projecting guard wall
configuration arranged along said forward edge 15
in assembled position, said guard wall configura-
tion projecting across said forward edge and con-
fining said forward edge of the rest means to
prevent articles being ironed from catching in
said edge. 20

2. In a flatiron, a heat applying member,
means for heating said member, a housing for
enclosing said heating means, means for securing
said housing to the heat applying member, said
housing comprising a sheet metal shell having a 25
heel portion and a depressed portion inwardly of
the heel portion, a rest means for supporting the
iron, said rest means comprising a sheet metal
member having a portion extending over the shell
provided with a boss in interlocking relation 30
with the depressed portion of the shell and hav-
ing an iron supporting portion projecting rear-
wardly beyond the heel portion of the shell, said
shell having spaced ribs confining the edges of
the overlapping portion of the rest means to pre- 35
vent articles being ironed from catching on said
edges.

3. In a flatiron, a heat applying member,
means for heating said member, a housing for
enclosing said heating means, means for securing 40
said housing to the heat applying member, said
housing comprising a sheet metal shell having a
heel portion and a depressed portion inwardly of
the heel portion, a rest means for supporting the
iron, said rest means comprising a sheet metal 45
member having a portion extending over the shell
provided with a boss in interlocking relation with
the depressed portion of the shell and having an
iron supporting portion projecting rearwardly
beyond the heel portion of the shell and flanges 50
extending laterally from said supporting portion
in supporting engagement with the heel portion
of the shell and spaced points of support lying in
the planes of said flanges, said shell having longi-
tudinally extending, spaced ribs coextensive with 55
and confining the contacting edges of the laterally
extending flanges of the rest means.

4. In a flatiron, a heat applying member,
means for heating said member, a housing for
enclosing said heating means, means securing the 60
housing to the heat applying member, a rest
means for supporting the iron, said housing com-
prising a sheet metal shell having a heel portion,
said rest means comprising a hollow sheet metal
member projecting rearwardly from the rear por-
tion of the shell, a tongue having an interlocking
connection between the forward end of the rest
member and the shell forwardly of the rear wall
of its heel portion, a handle having a portion in-
terlocked with said connection, and a terminal 70
housing interlocked with said rest member and
by said handle interlocked with said connection. 65

5. In a flatiron, a heat applying member, means
for heating said member, a housing for en-
closing said heating means, means securing the 75

housing to the heat applying member, a rest means for supporting the iron, said housing comprising a sheet metal shell having a heel portion, said rest means comprising a hollow sheet metal member projecting rearwardly from the rear portion of the shell, said shell having a recess in its upper surface inwardly of the heel portion, said rest member having a tongue projecting over the shell inwardly from the heel portion and having a projecting portion seated within the recess in the shell, said tongue having a recess therein, a terminal housing having a projecting portion received in the tongue recess, a handle having a supporting strap interlocked with the terminal housing and having a portion seated within the tongue recess, and means for clamping said tongue in said shell recess and said handle strap portion in said tongue recess, said handle supporting strap retaining the projecting portion of the terminal housing between itself and a side of said tongue recess.

6. In a flatiron, a heat applying member, means for heating said member, a housing for enclosing said heating means, means securing the housing to the heat applying member, a rest means for supporting the iron, said housing comprising a sheet metal shell having a heel portion, said rest means comprising a hollow sheet metal member projecting rearwardly from the rear portion of the shell, said shell having a plurality of spaced recesses in its upper surface inwardly of the heel portion, said rest member having a tongue projecting over the shell inwardly from the heel portion and having projecting portions seated within the recesses in the shell, said tongue having a plurality of spaced recesses therein, a handle having supporting straps seated within a pair of the tongue recesses, means for clamping said tongue in said shell recesses and said handle straps in said pair of tongue recesses.

7. In the combination of claim 5 wherein said clamping means comprises a lug projecting from the handle supporting strap and passing through aligned openings in the tongue of the rest member and the shell.

8. In a flatiron, a heat applying member, means for heating said member, a housing for enclosing said heating means, means for securing the housing to the heat applying member, a rest means for supporting the iron, said housing comprising a sheet metal shell having a groove extending longitudinally in the median plane of the shell, a handle having a supporting strap portion extending longitudinally of the shell and seated in said groove, said rest means comprising a sheet metal member having a forwardly projecting portion seated within said groove and interposed between the strap portion and the base of said groove, said forwardly projecting portion of the rest member and the base of said groove having aligned openings, and a lug on said strap portion of the handle passing through said aligned openings into clamping engagement with the inner surface of the shell to secure the handle and the rest member to said shell.

9. In a flatiron, a heat applying member, means for heating said member, a shell for enclosing said heating means, means securing the shell to the heat applying member, a rest member for supporting the iron, said shell and said rest member comprising individual sheet metal pieces

formed for ready assembly in rigid interlocking relation with each other, a terminal housing on said shell, and a sheet metal member for reenforcing the rest member, said reenforcing member having an interlocking connection with said shell and having a portion held in supporting interlocked engagement with the rest member, by a projection of said terminal housing.

10. In a flatiron, a heat applying member, means for heating said member, a housing for enclosing said heating means, means securing the housing to the heat applying member, a rest means for supporting the iron, said housing comprising a sheet metal shell having a heel portion, said rest means comprising a hollow sheet metal member projecting rearwardly from the rear portion of the shell and extending over the shell, the material of said shell being depressed at a predetermined point to provide a recess therein, the sheet material of said rest means being depressed above said shell recess and providing an opposite projecting portion extending into interlocking relationship with said shell recess, a handle member having a flanged lower portion extending into interengaging relationship into the said recess formed on the said rest means and clamping means for retaining said elements in said respective recesses.

11. In a flatiron, a heat applying member, means for heating said member, a shell for enclosing said heating means, means securing the shell to the heat applying member, and a rest member for supporting the iron, said shell and said rest member comprising individual pieces of sheet material formed for ready assembly with each other, the rest member having an iron supporting rest portion extending rearwardly from the shell when assembled and a forwardly extending portion overlying the shell and merging into the shell at points of contact, said shell having a projecting guard wall configuration comprising ridges extending outwardly a substantial distance beyond the normal plane of the shell and disposed longitudinally of the shell coextensive with the forwardly extending portion of said rest member, said ridges being spaced laterally to abut the edges of said forwardly extending portion of the rest member.

12. In a flatiron comprising a heat applying member, heating means, a housing for enclosing said heating means, and a rest means for supporting the iron, said housing comprising a sheet metal shell having a groove extending longitudinally of the median plane of said shell and terminating short of the rear end of said shell to provide an abutment defined by the rear extremity of said groove, a handle construction having a supporting strap portion extending longitudinally of the shell and seated in said groove, said rest means comprising a sheet metal member having a forwardly projecting portion extending above the shell and provided with a depressed portion extending within the rear portion of said groove only, the rear portion of said groove being substantially deeper and receiving said depressed portion with its top surface substantially in the plane of the forward portion of the groove, and means holding said supporting strap in said groove to maintain said rest means in operative position.

BERNHART A. BENSON.
